UNITED STATES PATENT OFFICE.

EWALD HÄHNEL, OF HOBOKEN, NEW JERSEY, ASSIGNOR TO PALM & FECHTELER, OF NEW YORK, N. Y.

DESIGN FOR ORNAMENTATION OF SEWING-MACHINES.

SPECIFICATION forming part of Design No. 12,552, dated November 1, 1881.

Application filed September 10, 1881. Term of patent 7 years.

To all whom it may concern:

Be it known that I, EWALD HÄHNEL, of Hoboken, in the county of Hudson and State of New Jersey, have invented a new and original Design for the Ornamentation of Sewing-Machines, of which the following is a specification.

This invention relates to a new and original design for the ornamentation of sewing-machines and other articles; and it consists in the novel grouping and configuration of parts, hereinafter more fully described.

In the accompanying illustration, Figures 1 and 2 are opposite views, in perspective, of a sewing-machine plate and arm having thereon my new design. Figs. 3 and 4 are top views, showing the ornamentation at the sides of the cloth-plate. Fig. 5 is a top view, showing the ornamentation at the back part of the sides of the cloth-plate. Fig. 6 is a side view of the ornamentation of the sewing-machine arm. Fig. 7 is a side view of the ornamentation of the top of the post supporting the sewing-machine arm. Fig. 8 is a side view, showing the ornamentation of the post that supports the sewing-machine arm. Figs. 9 and 12 are side views of the ornamentation of the different sides of the needle-carrying portion of the sewing-machine arm. Fig. 10 is a front view of the ornamentation for the front of the needle-carrying portion of the sewing-machine arm. Fig. 11 is a top view of the ornamentation at the base of the post of the sewing-machine arm.

The letter A represents the ornamentation for each side of the cloth-plate toward its front end. It consists of slender tendrils entwining with each other and bearing slim pointed leaves and bunches of flowers, like sprays of lilies of the valley, as shown.

The figure B represents the ornamentation for each side of the cloth-plate back of the figure A. It consists of a pair of tendrils on each side, whose stems cross each other, one tendril on each side bearing lilies of the valley and the other the leaves of the same plant, the tendrils twining with each other toward their ends.

The figure C shows the ornamentation which decorates the sides of the sewing-machine arm, and consists of slender tendrils bearing sprays of lilies of the valley, with their leaves, which encircle and contain an oval band, on which

the name of the machine (in this case "Wilson") is printed.

The figure D shows the ornamentation for one side of the needle-carrying portion of the sewing-machine arm, and D' shows the ornamentation for the other side of the same. Each of these figures consists of a spray of lily of the valley, the two sprays being very similar, but the figure D' being somewhat shorter than D.

The figure E shows the ornamentation of the front of the needle-bearing portion of the sewing-machine arm, and consists of a bunch of sprays of lily of the valley, bearing the flowers and leaves appropriate to that plant, and tied together at the bottom by what appears to be a small ribbon.

The figure F shows the ornamentation of the upper part of the post supporting the sewing-machine arm, and consists of a circular rosette having projecting therefrom, at right angles to each other, four buds of the lily of the valley, each projecting between two leaves of the same plant.

The figure G shows the ornamentation of the main portion of the post supporting the sewing-machine arm, and consists of a bunch of lily-of-the-valley sprays tied together by a cord or ribbon.

The figure H shows the ornamentation just at the base of the post supporting the sewing-machine arm, below the figure G, and consists of a small spray of lily of the valley bearing its buds and leaves.

I claim—

1. The design for the ornamentation of sewing-machines, consisting of the figure A, substantially as shown.

2. The design for the ornamentation of sewing-machines, consisting of the figure B, substantially as shown.

3. The design for the ornamentation of sewing-machines, consisting of the figures A and B, substantially as shown.

4. The design for the ornamentation of sewing-machines, consisting of the figure C, substantially as shown.

5. The design for the ornamentation of sewing-machines, consisting of the figure D, substantially as shown.

6. The design for the ornamentation of sew-

- ing-machines, consisting of the figure E, substantially as shown.
7. The design for the ornamentation of sewing-machines, consisting of the figure F, substantially as shown.
8. The design for the ornamentation of sewing-machines, consisting of the figure G, substantially as shown.
9. The design for the ornamentation of sewing-machines, consisting of the figure H, substantially as shown.
10. The design for the ornamentation of sewing-machines, consisting of the figures F, G, and H, substantially as shown.
11. The design for the ornamentation of sewing-machines, consisting of the figures C, F, G, and H, substantially as shown.
12. The design for the ornamentation of sewing-machines, consisting of the figures C, D, D', and E, substantially as shown.
13. The design for the ornamentation of sewing-machines, consisting of the figures A, B, C, D, D', E, F, G, and H, substantially as shown.

EWALD HÄHNEL.
